UNITED STATES PATENT OFFICE.

EDWARD BERGMAN, OF NEW YORK, N. Y., ASSIGNOR TO C. BRANDES, INC., OF NEW YORK, N. Y., A CORPORATION OF NEW YORK.

WINDING CHUCK.

Application filed August 11, 1922. Serial No. 581,155.

To all whom it may concern:

Be it known that I, EDWARD BERGMAN, a citizen of the United States, residing at New York, in the county of New York, State of New York, have invented certain new and useful Improvements in Winding Chucks; and I do hereby declare the following to be a full, clear, and exact description of the invention, such as will enable others skilled 10 in the art to which it appertains to make and use the same.

This invention relates to machines or tools for winding electro-magnets and has for its principal object the provision of a 15 chuck which is especially adapted for holding and properly positioning electro-magnet cores to facilitate winding operations thereon.

A further object is the provision of a 20 chuck of the above mentioned character into which an electro-magnet core can be very quickly inserted and secured in position for the winding operation, and requiring no skilled manipulation.

25 A further object is the provision in such a chuck of simple and suitable means for holding the starting end of the magnet wire during the winding operation.

The structure constituting the preferred 30 embodiment of the invention, as described in detail hereinafter, accomplishes all the aforementioned objects, and comprises, briefly, a rotatable face-plate having means for properly locating or positioning an elec- 35 tro-magnet core, a securing member overlying the face-plate and in threaded engagement therewith and having an opening which is arranged to permit the insertion of the magnet core into engagement with the 40 positioning means on the face-plate. With the magnet core thus inserted, the securing member may be rotated with respect to the face-plate and, by reason of its thread engagement therewith, the core may be clamped 45 between the face-plate and the securing member, all in a manner which will be clearly shown. An important, though simple, feature of the invention resides in the provision of one or more spring clips which 50 are, preferably, located on the periphery of the securing member, the purpose of which is to hold the starting end of the magnet wire during the winding operation.

The invention will be more clearly understood from the following detailed descrip-

tion with reference to the accompanying drawing, in which,

Fig. 1 is a view, partly in elevation, and partly in cross-section of an assembled winding chuck in accordance with the preferred 60 embodiment of the invention;

Fig. 2 is a front elevation of the chuck shown in Fig. 1;

Fig. 3 is a front elevation of the face-plate of the chuck;

Fig. 4 is a front elevation of the nest-plate; and,

Fig. 5 is a front elevation of the securing member or ring.

Referring more particularly to Figs. 1 70 and 2, the shaft 1 is that of a winding machine and is journaled in the bearing 2, suitable provision, not shown, being made for rotating the shaft at relatively high speed.

A face-plate 3 is rigidly secured to the 75 shaft 1 and rotatable therewith. This face-plate may be of machine steel and has a left-hand screw thread on its periphery as indicated at 4.

A steel nest-plate 5, which is shown more 80 clearly in Fig. 4 is secured by flat head screws 6 to the face of the face-plate. The nest-plate has an aperture 5' of suitable size and contour to fit one leg of the angle-shaped electro-magnet core 7 on which the winding is 85 to be placed. The magnet core 7 is shown in Fig. 4 in order to illustrate the fact that the winding receiving portion is located coaxially with the nest-plate and face-plate by virtue of the aperture 5'. A side elevation 90 of the magnet core 7 is shown in Fig. 1, and a front elevation thereof is shown in Fig. 2, in both of which views the magnet core is shown secured in the chuck. The magnet core 7 has two spool heads 8 and 9 between 95 which the magnet winding is placed.

An annular securing member 10, which is preferably of machine steel, is provided with an inside screw thread as shown at 4, whereby it engages the face-plate 3 and is rotatable with respect thereto, and at the same time adjustable in a direction parallel with the axis of shaft 1. This securing member has an aperture 10' of suitable size to permit the insertion therethrough of the vertical leg of the magnet core into the aperture 5' of nest-plate 5. But with the aperture 10' positioned as indicated in Fig. 2 the magnet core could not be so inserted as will be evident from an examination of Fig. 2. If, however,

the securing member 10 is rotated with respect to the face-plate 3 into a position wherein the portion 10 of the aperture 10' registers with aperture 5', the vertical leg 5 of the magnet core may be inserted in the chuck as shown in Figs. 1 and 2.

Since the screw thread 4 is left handed, a counter clockwise turn of the securing member 10, as viewed in Fig. 2, will effect a movement of the overlying portion thereof toward the face of the face-plate, and as will be obvious, the vertical leg of the magnet core will be clamped between the securing member and the face-plate. In Fig. 2, the magnet core is shown thus clamped in the chuck and ready for the winding operation.

A stop 11 is rigidly secured to the back of the face-plate, and a pin 12 carried by the securing member 10 cooperates with the stop 11 to limit the rotary movement of the securing member with respect to the face-plate. When pin 12 engages stop 11, the enlarged portion 10^a of aperture 10' registers with aperture 5'.

25 A pair of spring clips 13 are attached to the periphery of the securing member 10 by means of screws 14. The function of these spring clips is to hold the starting end of the magnet wire during the winding operations. The end of the wire is slipped under one of the spring clips and held by the tension of the spring. It is not essential to have more than one of these spring clips, but it is found convenient to have two.

35 It is thought that the operation of winding the magnet will be readily understood without further description.

The nest-plate 5 is not essential to the invention, as a recess 5' could be milled in 40 the face of the face-plate as will be quite evident. But the provision of the nest-plate renders the structure more economical to manufacture.

45 The rapidity with which the magnet cores may be secured in and removed from this chuck will, it is thought, be apparent to those skilled in the art, and the simplicity of the device renders it readily operable by the most unskilled labor.

50 As the invention can be readily embodied in many alternative forms, it is not to be construed as limited to the form described, but only by the scope of the appended claims.

I claim:

55 1. A rotatable chuck for winding electro-magnets, comprising a member having a recess adapted for receiving and properly positioning an electro-magnet core with respect to the axis of rotation of the chuck, 60 and a securing member for the electro-magnet core, said securing member having an aperture adapted to permit a portion of the core being passed therethrough into said recess, said securing member being operable to 65 clamp said core in said recess.

2. In a winding chuck, a rotatable member having means for receiving and properly positioning a magnet core, and a securing member having an aperture through which a portion of said magnet core may be inserted 70 to engage with said means, said securing member being movable into a plurality of positions relative to said rotatable member and adapted in certain of said positions to permit the insertion of said magnet core into engagement with said means, and operable in certain other of said positions to secure said magnet core in the chuck.

3. In a winding chuck, a rotatable face-plate having a recess for receiving and 80 properly positioning a magnet core so that the winding receiving portion of the core is substantially coaxial with said face plate, a securing member having an aperture adapted to permit a portion of said magnet core being inserted therethrough and into said recess, said securing member and said face-plate being jointly operable to clamp said magnet core in said recess.

4. In a winding chuck, a rotatable face-plate having a recess for receiving and properly positioning a magnet core so that the winding receiving portion of the core is substantially co-axial with said face-plate, a securing member having an aperture 95 adapted to permit a portion of said magnet core being inserted therethrough and into said recess, said securing member having a screw thread whereby it is adapted to rotate with respect to said face-plate and simultaneously move in a direction parallel to the axis thereof whereby said magnet core may be clamped in said recess.

5. In a winding chuck, a rotatable face-plate having a recess for receiving and prop-105 erly positioning a magnet core so that the winding receiving portion of the core is substantially co-axial with said face-plate, said face-plate having a screw thread on its peripheral portion, a securing member hav-110 ing an aperture adapted to permit a portion of said magnet core being insulated therethrough and into said recess, said securing member having a screw thread engaging

115 with the screw thread on said face-plate whereby said securing member is adapted to rotate with respect to said face-plate and to simultaneously move in a direction parallel to the axis thereof whereby said magnet core may be clamped in said recess.

6. In a winding chuck, a rotatable face-plate having means for receiving and prop-120 erly positioning a magnet core so that the winding receiving portion of the core is sub-125 stantially co-axial with said face-plate, means operable jointly with said face-plate for securing said magnet core, and a spring clip for holding the starting end of the wire during the winding operation.

7. In a winding chuck, a rotatable face-

plate, a nest-plate secured to the face of said face-plate, said nest-plate having an aperture proportioned to receive and properly position the core of an electro-magnet, and a securing member overlying said nest-plate and in threaded engagement with said face-plate, said securing member having an aper-

ture through which a portion of the magnet core may be passed for insertion into the aperture in said nest-plate, said securing member being operable by rotation to clamp said magnet core against said face-plate. 10

In testimony whereof I affix my signature.
EDWARD BERGMAN.
